DRAW WORKS HAVING DUAL DRIVE

William D. Davidson, Los Angeles, Calif., assignor to Emsco Derrick & Equipment Company, Los Angeles, Calif., a corporation of California

Application December 16, 1938, Serial No. 246,141

9 Claims. (Cl. 255—19)

My invention relates to rotary drawworks of the type commonly employed in the well drilling industry for hoisting various tools, drill pipe, or casing and for driving a rotary machine. At the present time oil wells are drilled to a considerable depth, and in order to raise and lower the various parts, particularly the drill pipe, at a maximum efficiency it is necessary to have a drawworks with a number of different speeds and powers. 5 When the well is relatively shallow the power required to raise the drill pipe is quite small as compared to the power required to raise the drill pipe when the well is at a considerable depth. The power required to drive the rotary machine is usually considerably less than that required to handle a long string of drill pipe, and therefore in the common type of drawworks now in use today employing a heavy steam engine there is considerable waste of power when the rotary 10 table is being rotated and the hoisting apparatus is not in operation.

It is an object of my invention to provide a rotary machine having a main engine and an auxiliary engine, either or both of which may be employed to operate the drawworks.

It is an object of my invention to provide a drawworks in which the auxiliary engine may be employed to operate the rotary machine even during the time that the hoisting apparatus is in operation. This is a valuable feature and enables various operations to be performed which can not be performed on the ordinary drawworks, such, for example, as "drilling up" to loosen a stuck drill pipe.

35 It is an object of my invention to provide a rotary drawworks and engine combination which employs two engines of smaller size and of less cost than standard in order that the first cost of the apparatus may be lower and in order that there may be greater economy in operation, this last mentioned feature being accomplished due to the fact that both engines are employed only when it is necessary to have their combined power.

45 It is a still further object of my invention to provide a rotary drawworks having a greater flexibility of drives and power in order that there may be a suitable drive available for handling heavy or light loads and for moving the same at the maximum economical rate of travel.

It is an object of my invention to provide a rotary drawworks in which two engine drives are provided, either of which may be employed so that in case of an emergency where one engine

fails the other may be employed, thus eliminating shut downs.

It is a still further object of my invention to provide a drawworks having means whereby the Robishaw reel may be operated, preferably independently of the other apparatus, so that it is unnecessary to have a number of shafts of the drawworks rotating.

It is a further object of my invention to provide a rotary drawworks in which all of the parts are idle when driving the rotary machine except those particular parts which connect the drive engine to the rotary machine. In this way considerable wear on the drawworks parts will be eliminated.

Other objects and advantages of my invention will become apparent during the course of the following description of the different forms in which my invention may be embodied. The principles of my invention may be embodied in other structures than those illustrated, and I therefore wish my invention to be broadly construed in accordance with the preceding statement of invention and appended claims and not to be limited to the details of construction of the forms of my invention which I have chosen for the purpose of illustrating the various features and advantages of my invention.

In the accompanying drawings:

Fig. 1 is an elevational view of the drawworks and drive means of my invention employed in a derrick, most of the parts of this view being diagrammatically shown.

Fig. 2 is a plan view of the drawworks and drive means of my invention, the main and auxiliary engines being diagrammatically illustrated.

Figs. 3, 4, and 5 are diagrammatic plan views illustrating other embodiments of my invention.

Referring to Figs. 1 and 2 in detail, the numeral 15 represents a derrick having a derrick floor 16 on which a rotary machine 17 is mounted and at one side of which a drawworks 18 incorporating the features of my invention is also mounted. The rotary machine has a rotary table 19 through which a string of drill pipe 20 rotated thereby is extended, this rotary machine 17 having a sprocket 21 which is driven by a chain 22 extended to the drawworks 18. The drill pipe 20 is raised or lowered by a travelling block 24 around which is extended a cable 25 which passes over a crown block 26 and then to the drawworks 18. The travelling block 24 is also used for raising or lowering various other parts around the derrick.

The drawworks 18 includes a base in the form

55

of frame structures 27, each of which includes an I-beam 28 which is preferably supported on a foundation 16a. These I-beams 28 are suitably secured together by cross-beams 29 to form a rigid structure. Each of the frame structures 27 includes, in addition to the I-beam 28, an upright structure designated by the numeral 30. My invention provides a jack shaft 33 which extends in a horizontal plane across the draw-works in a position near the rear part thereof, being rotatably supported by bearings 34 mounted on the rearward upright beams 30a of the upright structures 30. The numeral 36 designates a line shaft which is mounted in a horizontal position parallel to the jack shaft but is in a forward position and a higher position than the jack shaft. This line shaft 36 is supported by bearings 37 mounted on the upper horizontal beams 30b of each upright structure 30. My invention also provides a drum shaft 40 which extends parallel to the other two shafts and is positioned in a plane in front of the line shaft but somewhat lower, as illustrated best in Fig. 1. The drum shaft, however, is in a plane slightly higher than the jack shaft 33. The drum shaft 40 is supported by bearings 41 secured to the front inclined member 30c of the upright structures 30. Thus drum shaft 40 is provided with a hoisting drum 43 of conventional type having brake structures 44 mounted at each end thereof and operated by suitable brake operating means of a type well known in the industry, and which, for the sake of clarity and simplicity, has not been illustrated.

The jack shaft 33 has a jack shaft drive sprocket 47 which is driven from a prime mover in the form of a main engine 48 through a sprocket chain 49. The sprocket 47 is rotatable on the jack shaft 33 but may be fixed to and caused to drive the jack shaft 33 by engaging a clutch 50. The clutch 50, as well as any of the other clutches of the apparatus, may be operated by clutch operating means well known in the industry and which may be applied by any skilled mechanic. For the sake of clearness and simplicity, the various clutch operating means have not been illustrated. The line shaft 36 may be driven from the jack shaft by a primary line shaft drive 51 or a secondary line shaft drive 52, the first mentioned line shaft drive including a sprocket 53 rotatably mounted on the jack shaft 33, a sprocket 54 fixed to the line shaft 36, and a sprocket chain 55 extending over the sprockets 53 and 54, and the second mentioned line shaft drive including a sprocket 57 rotatably mounted on the jack shaft 33, a sprocket 58 fixed to the line shaft 36, and a sprocket chain 59 extending around these two sprockets. Either drive may be employed, depending upon the position of a clutch 60 which may be operated through clutch operating mechanism (not shown) to cause either the sprocket 53 or the sprocket 57 to be locked to and driven by the jack shaft 33.

The drum shaft 40 may be driven by a primary drum shaft drive 64 or a secondary drum shaft drive 65, the former of which includes a sprocket 66 fixed to the line shaft 36, a sprocket 67 rotatable on the drum shaft 40, and a sprocket chain 68 extending around the sprocket 66 and 67, and the latter drive including a sprocket 70 fixed to the line shaft 36, a sprocket 71 rotatable on the drum shaft 40, and a sprocket chain 72 extending around the sprockets 70 and 71. The primary drum shaft drive 64 may be brought into operation by the actuation of a clutch 73 mounted

on the drum shaft 40 or the secondary drum shaft drive means may be brought into operation by the operation of a clutch 74 also mounted on the drum shaft 40.

The rotary drive means of the invention includes a rotary drive sprocket 78 which is rotatably mounted on the extending end of the jack shaft 33, but which may be locked thereto by the operation of a clutch 79. In the preferred form of my invention an idler 80 is rotatably mounted on an extending end of the drum shaft 40 and has a sprocket element 81 over which the chain 22 to the rotary machine 17 is extended. The rotary drive sprocket has a sprocket element 82 and the idler has a sprocket element 83, and a sprocket chain 84 extends around these sprocket elements so that the idler 80 may be driven.

My invention also provides an auxiliary drive means in the form of an auxiliary engine 85. In the preferred form of my invention the main engine 48 is capable of delivering the greater power, while the auxiliary engine 85 is preferably only of sufficient horse power to properly drive the rotary machine or Robishaw drive. The auxiliary engine has a primary drive in the form of a sprocket 86 rotatably mounted on the auxiliary engine shaft 87 which includes a clutch diagrammatically shown at 89 which when disengaged allows the shaft to rotate independent of the auxiliary engine. Extending over the sprocket 86 and also over a sprocket element 88 of the drive sprocket 78 is a sprocket chain 90 whereby the rotary drive sprocket 88 may be driven by the auxiliary engine 85 when a clutch 91 is in mesh. The auxiliary engine also has a secondary auxiliary engine drive and includes a sprocket 92 rotatably mounted on the auxiliary engine shaft 87, a sprocket 93 rotatably mounted on the jack shaft 33, and a sprocket chain 94 extending around these two sprockets. The sprocket 92 may be locked to and driven by the shaft 87 by engaging the clutch 95, and the sprocket 93 may be fixed to and drive the jack shaft 33 by engaging a clutch 96. The auxiliary engine also has a Robishaw reel drive for the purpose of operating a Robishaw reel 98 which is positioned as diagrammatically shown in Figs. 1 and 2, and which includes a drum 99 on which a cable 100 may be wound, which cable extends to the crown of the derrick and may be employed for the raising and lowering of certain parts. The Robishaw drive includes a Robishaw drive sprocket 102 rotatably mounted on the auxiliary engine shaft 88, a sprocket 103 mounted on a shaft 104 of the Robishaw drive 98 on which the drum 99 is mounted, and a sprocket chain 105 which extends over these two sprockets. The sprocket 102 may be driven by the shaft 87 upon engagement of a clutch 106.

The drawworks combination of my invention has a large number of different drives which will now be described. The main engine 48 may be employed for driving the host or drum 43 by engaging the clutch 50 and the clutch 60 with either of the sprockets 53 or 57 and with either of the clutches 73 or 74 in engagement. At this time the clutches 79, 91, 95, 96, and 102 may be disengaged. The main engine may be employed for driving the rotary machine by engaging the clutch 50 and the clutch 79 and by disengaging the clutches 60, 91, 95, and 106. The main engine may be employed for driving the drum and the auxiliary engine employed for simultaneously operating the rotary machine by engaging the clutches 50 and 60 and the clutch 91. It will

be seen that in this way the jack shaft 33 and the drive sprocket 78 are both independently driven. This operation may be desirable, such, for example, as when drilling in an upward direction, in order to release a stuck drill string. The main engine and the auxiliary engine as a helper may be employed for driving the drum 43 by engaging the clutches 50, 60, 95, and 96. At this time both the main engine 48 and the auxiliary engine 85 are employed to drive the jack shaft 33.

The auxiliary engine may be employed to drive the drum 43 by engaging the clutches 95 and 96 while the clutches 50 and 91 are disengaged. This drive arrangement may be desirable when very small loads are being carried or when the main engine 48 is disabled. The auxiliary engine 85 may be independently employed to drive the rotary machine 17 by engaging the clutch 91, the clutches 79, 95, 96, and 106, as well as the clutch 50, being disengaged. The auxiliary engine 85 may be separately employed to drive the Robishaw reel 98 by engaging the clutch 106, all other clutches being disengaged.

In Fig. 3 I have shown a form of my invention in which the sprockets 92 and 102 are formed integrally to form a sprocket member generally designated by the numeral 115 and which are locked to the shaft 87 by the clutch 91. In this form of my invention it is desirable to rotatably mount the sprocket 103 on the Robishaw shaft 104 and to provide a clutch 116 for fixing the same to the shaft. This is desirable in order that this clutch may be disengaged when the clutch 91 and clutch 96 are in engagement.

In the form of my invention shown in Fig. 4 the shaft 81 is made separate from the auxiliary engine 85 and is provided with a sprocket 117 adapted to be driven by a chain 118 which extends around a sprocket 119 mounted on the auxiliary engine sprocket shaft 87a. In this form of my invention the auxiliary engine 85 may be conveniently mounted any suitable distance from the shaft 87.

In the form of my invention shown in Fig. 5 the Robishaw drive sprocket 102 is provided in the form of a sprocket 102a which is rotatably mounted on the jack shaft 33 and adapted to be locked thereto and driven thereby in the operation of a clutch 106a. In this form of my invention the auxiliary engine 85 has but a single sprocket 86a which is fixed to the shaft 87.

In the preceding description the terms "main" and "auxiliary" are employed in a relative sense; and it is within the scope of my invention to have the auxiliary engine 85 of as great or greater horse power than the main engine 48. Also the terms "primary" and "secondary" as applied to certain of the drives are employed to distinguish one from the other. Broadening terms have been used in the description and claims to broadly define my invention in order that the claims may be commensurate with the scope of my invention.

I claim as my invention:

1. In combination: a drawworks having a drawworks shaft, a hoisting drum, drum drive means whereby said shaft may drive said drum, and clutch means for said drum drive means; a drawworks shaft drive means whereby a main engine may drive said drawworks shaft; drawworks shaft drive means clutch for said drawworks shaft drive; rotary drive means having a rotary drive sprocket rotatable on said drawworks shaft; primary auxiliary engine drive means shaft; primary auxiliary engine drive means clutch for locking said rotary drive sprocket; and Robishaw reel drive means whereby said auxiliary engine may drive a Robishaw reel.

means whereby an auxiliary engine may drive said rotary machine drive sprocket; and clutch means for locking said rotary drive sprocket to said drawworks shaft.

2. In combination: a drawworks having a drawworks shaft, a hoisting drum, drum drive means whereby said shaft may drive said drum, and clutch means for said drum drive means; a drawworks shaft drive means whereby a main engine may drive said drawworks shaft; drawworks shaft drive means clutch of said drawworks shaft drive; rotary drive means having a rotary drive sprocket rotatable on said drawworks shaft; primary auxiliary engine drive means whereby an auxiliary engine may drive said rotary machine drive sprocket; and secondary auxiliary engine drive means whereby said auxiliary engine may drive said drawworks shaft.

3. In combination: a drawworks having a drawworks shaft, a hoisting drum, drum drive means whereby said shaft may drive said drum, and clutch means for said drum drive means; a drawworks shaft drive means whereby a main engine may drive said drawworks shaft; drawworks shaft drive means clutch for said drawworks shaft drive; rotary drive means having a rotary drive sprocket rotatable on said drawworks shaft; primary auxiliary engine drive means whereby an auxiliary engine may drive said rotary machine drive sprocket; secondary auxiliary engine drive means whereby said auxiliary engine may drive said drawworks shaft; and clutch means for locking said rotary drive sprocket to said drawworks shaft.

4. In combination: a drawworks having a drawworks shaft, a hoisting drum, drum drive means whereby said shaft may drive said drum, and clutch means for said drum drive means; a drawworks shaft drive means whereby a main engine may drive said drawworks shaft; drawworks shaft drive means clutch for said drawworks shaft drive; rotary drive means having a rotary drive sprocket rotatable on said drawworks shaft; primary auxiliary engine drive means whereby an auxiliary engine may drive said rotary machine drive sprocket; clutch means for locking said rotary drive sprocket to said drawworks shaft; and Robishaw reel drive means whereby said auxiliary engine may drive a Robishaw reel.

5. In combination: a drawworks having a drawworks shaft, a hoisting drum, drum drive means whereby said shaft may drive said drum, and clutch means for said drum drive means; a drawworks shaft drive means whereby a main engine may drive said drawworks shaft; drawworks shaft drive means clutch for said drawworks shaft drive; rotary drive means having a rotary drive sprocket rotatable on said drawworks shaft; primary auxiliary engine drive means whereby an auxiliary engine may drive said rotary machine drive sprocket; secondary auxiliary engine drive means whereby said auxiliary engine may drive said drawworks shaft; and clutch means for locking said rotary drive sprocket to said drawworks shaft; and Robishaw reel drive means whereby said auxiliary engine may drive a Robishaw reel.

6. In combination: a drawworks having a drawworks shaft, a hoisting drum, drum drive means whereby said shaft may drive said drum, and clutch means for said drum drive means; a drawworks shaft drive means whereby a main engine may drive said drawworks shaft; drawworks shaft drive means clutch for said draw-

- 5 works shaft drive; rotary drive means having a rotary drive sprocket rotatable on said drawworks shaft; primary auxiliary engine drive means whereby an auxiliary engine may drive said rotary machine drive sprocket; primary auxiliary engine drive clutch means for said primary auxiliary engine drive means; secondary auxiliary engine drive means whereby said auxiliary engine may drive said drawworks shaft; secondary auxiliary engine drive clutch means for said secondary auxiliary engine drive means; and clutch means for locking said rotary drive sprocket to said drawworks shaft.
- 10 7. In combination: a drawworks having a drawworks shaft, a hoisting drum, drum drive means whereby said shaft may drive said drum, and clutch means for said drum drive means; a drawworks shaft drive means whereby a main engine may drive said drawworks shaft; drawworks shaft drive means clutch for said drawworks shaft drive; rotary drive means having a rotary drive sprocket rotatable on said drawworks shaft; primary auxiliary engine drive means whereby an auxiliary engine may drive said rotary machine drive sprocket; primary auxiliary engine drive clutch means for said primary auxiliary engine drive means; secondary auxiliary engine drive means whereby said auxiliary engine may drive said drawworks shaft; and secondary auxiliary engine drive clutch means for said secondary auxiliary engine drive means.
- 15 8. In combination: a drawworks having a drawworks shaft, a hoisting drum, drum drive means whereby said shaft may drive said drum, and clutch means for said drum drive means; a drawworks shaft drive means whereby a main engine may drive said drawworks shaft; drawworks shaft drive means clutch for said drawworks shaft drive; rotary drive means having a rotary drive sprocket rotatable on said drawworks shaft; primary auxiliary engine drive means whereby an auxiliary engine may drive said rotary machine drive sprocket; primary auxiliary engine drive clutch means for said primary auxiliary engine drive means; secondary auxiliary engine drive means whereby said auxiliary engine may drive said drawworks shaft; secondary auxiliary engine drive clutch means for said secondary auxiliary engine drive means; clutch means for locking said rotary drive sprocket to said drawworks shaft; Robishaw reel drive means whereby said auxiliary engine may drive a Robishaw reel; and Robishaw reel drive clutch means for said Robishaw reel drive means.

CERTIFICATE OF CORRECTION.

Patent No. 2,170,365.

August 22, 1939.

WILLIAM D. DAVIDSON.

It is hereby certified that error appears in the printed specification of the above numbered patent requiring correction as follows: Page 3, second column, line 11, claim 2, for the word "of" read for; and that the said Letters Patent should be read with this correction therein that the same may conform to the record of the case in the Patent Office.

Signed and sealed this 26th day of September, A. D. 1939.

Henry Van Arsdale,

Acting Commissioner of Patents.

(Seal)
